UNITED STATES PATENT OFFICE.

ELBERT M. CHAPPELL, OF HARTSVILLE, SOUTH CAROLINA.

DEVICE FOR USE IN SHAVING.

Application filed September 19, 1922. Serial No. 589,259.

This invention relates to a device for use in shaving and is adapted and intended to furnish the most satisfactory conditions for use both at home and when traveling. It 5 embodies a light sheet metal housing of symmetrical form, the surface of which may be given any suitable attractive coating or finish, of such shape and size as to be easily carried in a suit case or hand bag and which 10 has normally within the lines of its main outer surfaces, one or more adjustable mirrors, an electric light, the rays of which are directed towards the space in front of the mirror and easily accessible means for receiving and holding a package of shaving soap and a shaving brush within it for transportation and for holding the brush in convenient position outside of the housing for use in shaving. It also includes means fold- 15 able to position within the outer margins of the surfaces of the housing for supporting it in proper position on a flat surface or from a hook or nail. The novel features will be more fully understood from the following description and claims taken with the accompanying drawings.

In the drawings:

Figure 1 is a front view of one embodiment of the invention with the cover open 30 and a brush shown in dotted lines hanging at the side;

Figure 2 is an end view of this form closed, looking from the left in Figure 1;

Figure 3 is a vertical section through the 35 center on line 3—3 of Figure 1;

Figure 4 is a horizontal section on the center line 4—4 of the form shown in Figure 1;

Figure 5 is a front view of a modified form with the cover open; and

Figure 6 is an end view of the form shown in Figure 5 looking from the right and showing a brush in dotted lines.

In the form shown in Figure 1 there is a housing 10 which may be composed of 45 any suitable metal such as thin sheet metal and which has greater length than height and greater height than thickness and in which the end portions are semi-spherical on horizontal lines having a form approxi- 50 mately oval in side view. Two circular openings 11 and 12 are formed in the front wall concentric with the semi-circular end portions leaving a narrow margin at the end portions in the front wall. Two mirrors 55 13 and 14 having circular marginal frames 15 and 16 of suitable metal are concentri-

cally arranged in these openings with their outer faces normally substantially in the same plane as the face of the front wall of the housing. These mirrors are pivoted on 60 vertical central lines through their centers to supporting rings 17 and 18 by pivot pins 19, 20, 21, 22 shown in dotted lines in Figure 1 connecting the frames 15 and 16 of the mirrors to the rings 17 and 18. The 65 rings 17 and 18 are pivoted on central horizontal lines to fixed parts of the front wall of the housing by pivot pins 23, 24. The rings 17 and 18 concentrically surround the mirrors and a sufficient space is left between 70 the margin of the mirrors and the rings and between the outer margins of the rings and the inner edges of the opening to permit the mirrors to turn either on a horizontal axis with the rings or on a vertical axis on the 75 rings or on both so as to get any adjustment of the mirrors desired. At the central portion of the front wall of the housing between the two mirrors there is a depression 25 which is of such size and depth that an 80 electric light bulb 26 may fit in it with its outer end within the plane of the outer surface of the front wall of the housing. There is an electric light socket 27 of usual form at the inner end of this depression to receive an electric light. It will be noted that by this arrangement the light generated by 85 light 26 will have its rays directed outwardly across the plane of the front wall of the housing and the normal plane of the mirrors 90 so as to strike the person in front of the mirror in the act of shaving without striking the mirrors. Electric current causing the operation of the electric light may be produced by any means so far as this in- 95 vention broadly considered is concerned but in the form shown in Figures 1 and 2 there is a plug socket 28 set into the end of the housing and adapted to receive the plug of well known form on the end of a drop 100 wire having the usual contact projections and this plug socket is connected to the lamp socket through a make and break contact mechanism 29 controlled by the push buttons 30 and 31 extending inwardly from 105 the surface of the front wall below the light and it will be understood that the usual electric light circuit may be connected to the device by the plug socket 29.

The cover 32 of the housing is hinged at 110 the rear and is adapted to turn up to a position substantially parallel to the back

wall of the housing. Its upper surface at wardly and inwardly at 61 and 62 forming its front edge is depressed sufficiently to lateral grooves. A separate flat extension receive a hook member 33 in the form of a member 63 fits its outer face between said wire pivoted at its ends 34 and 35 to the 70 cover and adapted to fold down in the depression within the marginal lines of the outer surface of the top for purposes of transportation. It has three upward bends 36, 37 and 38 which are adapted to engage 75 a hook or nail supporting the device with the cover open. On the inner face of the cover there are four curved hook members 39, 40, 41 and 42 adapted to support a celluloid container 43 for shaving soap and 80 a similar container 44 for a shaving brush, these hook members being yieldingly held in the position shown in Figure 3 with their free ends near the inner surface of the cover by springs 45. The cover has at its forward 85 free edge a catch 46 of spring metal having a depression in its outer face adapted to engage the projection 47 on the inner face of the front wall and yieldingly hold the cover in closed position.

25 An elongated supporting member 48 enters the housing on its central line from one end at the back wall and it is composed of an elongated narrow flat strip having rigid therewith flat headed pins 49 and 50 projecting from its face next to the rear wall and secured to the rear wall there is a member 51 having a longitudinal slot wide enough to receive the shank of pins 49 and 50 with lateral extensions of the slot at the 90 bottom sufficiently wide to receive the heads of the pins 49 and 50 thus serving as substantially a tongue and groove sliding connection for holding the holder 48. The longitudinal portion of the holder 48 at its outer end is forked comprising two arms 52 and 53 in a horizontal plane, the arm 53 extending laterally and forwardly and leaving a sufficient space between the two arms to receive the contracted portion of handle of 95 the shaving brush so as to support it at the side of the housing. The outer ends of the arms 52 and 53 are turned upward as shown at 54 in Figure 1 so as to prevent accidental displacement of the brush longitudinally, 100 the brush 55 being illustrated in dotted lines. This support 48 may be moved by longitudinal sliding in its supporting groove 52 until the arms 52 and 53 project outwardly as shown in Figure 4 for use in shaving but 105 it may also be moved in the reverse direction so that the arms enter the housing 110 through slot 56.

The bottom wall 57 of the housing 10 is 115 preferably made at a slight incline to the front wall so as to permit of rest on a flat support with its front wall at a slight angle to vertical and a longitudinal support 58 is hinged at 59 to the back of the housing at the top and its lower portion 60 is bent 120 inwardly and its side margins are bent out-

In the form of the invention shown in Figures 5 and 6 the housing 67 is rectangular in outline and has in its front wall a single mirror 68 which is mounted centrally. The mirror is connected by pivot pins 69 and 70 to ring 71 which in turn is connected to the housing by pivot pins 72, 73, the arrangement being similar to that heretofore described for the mirrors shown in Figure 1. 90 In this form there are two depressions 74, 75 in the front wall, one on each side of the mirror and they are of the same type as the depression 25 in the form shown in Figure 1 and are adapted to receive two incandescent electric lights. In this instance there are two sets of push buttons 76 for turning on and off the current to the two electric light sockets. The cover 77 is hinged to the rear of the housing 67 as in the 100 first mentioned form and has similar hooks 78 for receiving and holding the soap container and the shaving brush. In this instance the support 79 for the brush corresponding to the support 48 of the first 105 form is similar in all respects to that above described but is mounted on the inner face of the cover 77 so that a slot in the end of the housing is not necessary in moving it out to projected position, as shown in Figure 5 for supporting the brush during shaving. In this form the cover 77 may be provided with an opening 80 to engage a nail or hook for supporting the device. This 110 form also is provided in its end with a plug socket 81 for connection to an electric circuit and that plug socket is connected to the make and break contacts operated by the push buttons and to the electric light sockets as described in connection with the first 115 form.

Although two embodiments of the invention have been shown for purposes of illustration it will be understood that it is not limited to the details shown beyond what is required by the following claims.

Having thus described my invention what I claim as new and desire to secure by Letters Patent is:

1. A device for use in shaving comprising 130

in combination, a portable housing having in its front wall a mirror pivotally supported for turning horizontally and vertically, an electric light socket in a depression 5 in said wall at one side of said mirror, means in the rear of said wall for connecting said socket in an electric circuit, and movable means connected to said housing for supporting it in position adapted to be 10 moved within the outer surface lines of said housing when not in use.

2. A device for use in shaving comprising in combination, a portable housing having in its front wall a mirror pivotally supported for turning horizontally and vertically, means in said housing for detachably holding and supporting a package of soap and a shaving brush, and an elongated member within said housing so connected there- 15 to as to permit longitudinal sliding movement and having a forked end of such form as to receive the handle of a shaving brush and support it projecting horizontally from the end of the housing in one position of 20 movement.

3. A device for use in shaving comprising in combination, a portable housing having in its front wall a circular opening and an oval depression at one side of said opening having a depth as great as the length of 30 the glass bulb of an electric light, an electric lamp socket at the bottom of said depression, a mirror in said opening, a concentric ring support in said opening surrounding 35 said mirror, pivotal connection between said ring and housing and between said ring and mirror at right angles to each other and on horizontal and vertical lines, and means for connecting said lamp socket in an elec- 40 tric circuit.

4. A device for use in shaving comprising in combination, a portable housing having in its front wall a mirror pivotally supported for turning horizontally and vertically, a hinged cover for said housing, spring pressed movable hook members in 45 said housing adapted to engage and releasably hold a soap container, and a shaving brush, a movable member in said housing having a forked end portion adapted to laterally engage and support a shaving brush and to be moved to a position with 50 its forked end projecting horizontally from the end of the housing.

5. A device for use in shaving comprising in combination, an elongated portable housing having semi-cylindrical ends with horizontal axes and circular opening in its front wall at the ends of said housings, circular 55 mirrors in said openings, pivot means supporting said mirrors in said openings permitting turning on a horizontal axis and on a vertical axis, and means for support- 60 ing said housing.

6. A device for use in shaving comprising in combination, an elongated portable housing having semi-cylindrical ends with horizontal axes and circular openings in its front wall at the ends of said housings, circular mirrors in said openings, pivot means 65 supporting said mirrors in said openings permitting turning on a horizontal axis and on a vertical axis, means for supporting said housing, and means for producing artificial light in a depression in the said front wall 70 between said mirrors.

7. A device for use in shaving comprising in combination, an elongated portable housing having semi-cylindrical ends with horizontal axes and circular openings in its front wall at the ends of said housing, circular mirrors in said openings, circular ring supports in said openings surrounding said mirrors, pivot connections between said mirrors and said supports and said supports and housing on longitudinal and vertical lines, an electric light socket in the bottom 80 of an oval-shaped depression in the surface of the front wall of said housing between 85 said mirrors, and means for connecting said socket in an electric circuit.

8. A portable shaving kit comprising in combination, a casing having a front wall which the user faces when shaving, said wall having a depression and an aperture 90 formed therein and the casing being provided with means for maintaining said wall in an upright position, an electric light socket secured within the depression provided 95 with a light bulb and means for supplying the same with current from a source in rear of the front wall, and a mirror mounted in the aperture for universal movement, no portion of the mirror or globe projecting 100 beyond the front wall when the kit is arranged for transportation.

9. A portable shaving kit comprising in combination, a casing having a front wall which the user faces when shaving, and a rear wall spaced therefrom, a cover for said casing hinged to its rear wall, means secured to the inner surface of said cover for receiving and attachably holding containers for soap and a shaving brush, the front wall of said casing having a depression and an aperture formed therein, an electric light socket secured within the depression provided with a light bulb and means for supplying the same with current from a source in rear of the front wall, and a mirror mounted in the aperture for universal movement, no portion of the mirror or globe projecting 110 beyond the front wall when the kit is arranged for transportation.

In testimony whereof I hereunto affix my 115 signature.

ELBERT M. CHAPPELL.
